UNITED STATES PATENT OFFICE.

FRANCES M. FAHL, OF GENESEO, NORTH DAKOTA.

WASHING-MACHINE TOY.

Application filed April 2, 1927. Serial No. 180,426.

This invention relates to a toy, and particularly to a toy designed to simulate a machine such as a washing machine. As is well known, full sized washing machines 6 are now commonly used and one type of washing machine has the general structure including a container within which is contained a clothes moving element, suitable mechanism being provided for operating 10 said element.

It is an object of this invention, therefore, to provide a very simple and inexpensive toy and one which will in a degree simulate a full sized washing machine.

15 It is another object of the invention to provide a toy comprising a small hollow body simulating a clothes container, the same having a mechanism mounted on the top thereof adapted to be operated by a suitable hand crank which will simulate a washing machine mechanism used to operate the clothes moving element of a washing machine.

It is more specifically an object of the invention to provide a small hollow member having a top adapted to simulate the clothes container of a washing machine, the same having a shaft mounted in a suitable bearing on its top, said shaft having a small 25 fly wheel thereon and also carrying a ratchet wheel with which a ratchet bar guided in a suitable yoke engages, which ratchet bar is pivotally connected to and operated by a hand lever pivoted to one side of the body.

30 These and other objects and advantages of the invention will be fully set forth in the following description made in connection with the accompanying drawings, in which like reference characters refer to similar parts throughout the several views and in which:—

Fig. 1 is a view in side elevation of the device, a portion thereof being broken away and other portions shown in vertical section, some of the parts being shown in different positions in dotted lines;

Fig. 2 is a top plan view of the device, a portion thereof being shown in a different position in dotted lines; and

50 Fig. 3 is a vertical section taken on line 3—3 of Fig. 1, as indicated by the arrows.

Referring to the drawings, a small body 5 is shown substantially of cylindrical shape, or which is tapered slightly toward its upper end, said body being supported upon a plurality of circumferentially spaced legs

6 secured thereto and adapted to rest upon the supporting surface 7. The member 5 is hollow so as to have a chamber 5^a therein and the body 5 is provided with a suitable lid 8. The lid 8 comprises a laterally swinging section 8^a pivoted to the top of the container by the pivot 9, said section 8^a being swingable as illustrated in Fig. 2, to give access to the chamber 5^a. A bearing 65 bracket 10 is secured to the lid 8 and while this bracket may be variously made, one simple form which has been found convenient in practice and which is illustrated in the drawing, is made from a strip of flat material having its end portions bent upwardly to form apertured lugs 10^a. A shaft 11 is journaled in the lugs 10^a and has secured at one end thereof a comparatively heavy fly wheel 12. While the shaft 11 and wheel 12 75 may be held in place by any suitable means, in the embodiment of the invention illustrated the same are shown as held in place by having the ends of the shaft provided with enlarged portions 11^a such as might be 80 formed by upsetting the ends of said shaft. A wheel 13 is secured to the shaft 11 inside of and adjacent the inner lug 10^a of the bracket 10. This wheel, as shown in Fig. 1, is in the form of a ratchet gear having pointed teeth of the usual ratchet type thereon. A yoke 14 is secured to the top 8 adjacent one side of the gear 13, which yoke is illustrated as a simple staple or U-shaped rod having its ends out-turned at the inner side 85 of the lid 8. A bar 15 extends through the yoke 14 and is provided on its under surface with spaced ratchet teeth 15^a, said bar extending across the top of or in line with the top of the gear 13 and being pivoted at one end to an intermediate point 90 in the lever 16 pivoted at its lower end by the pivot 17 to a bracket or clip 18 secured to the side of the body 5 adjacent the bottom thereof. The lever 16 is shown as having spaced sides and a socket portion at its upper end in which is disposed the handle portion 16^a. The bar 15 at its free end has a laterally turned portion 15^b preventing its movement through the yoke 14. 100

In operation the lever 16 will be oscillated by gripping the handle portion 16^a thereof and the bar 15 will be reciprocated in the yoke 14. As the bar is drawn outwardly or to the right as shown in Fig. 1, gravity will cause the bar to rest on the gear 13 and the teeth 15^a will engage said teeth and rotate 110

said gear, thus rotating the shaft 11 and the fly wheel 12. As the bar is moved inwardly, the inclined sides of the teeth 15^a will ride over the inclined sides of the teeth on gear 13 and as said bar is not very heavy, the bar will have little or no rotating effect on the wheel or gear 13. The fly wheel 12 keeps the shaft 11 rotating in the same direction. As the bar 15 again moves outwardly, it will impart another rotating impulse to the shaft 11 and the shaft 11 will thus be kept rotating. The operation of the mechanism simulates in a way the operation of a full sized washing machine mechanism and children thus can derive great pleasure from operating the toy. The section 8^a of the lid may be moved to give access to the chamber 5^a and the child can place doll clothes or other articles in the chamber 5^a and thus play at washing.

While any suitable materials may be used for the device, in practice it has been found convenient to make the body 5, lugs 6 and cover 8 as well as the handle 16^a of wood and to make the other parts of metal.

From the above description it is seen that applicant has provided a very simple structure of toy and one which will give a great deal of enjoyment to children. The parts are few and of simple construction and the device can be easily made and assembled and marketed quite inexpensively. The device has been amply demonstrated in actual practice and found to be very successful.

It will, of course, be understood that various changes may be made in the form, details, arrangement and proportions of the parts, without departing from the scope of applicant's invention, which, generally stated, consists in a device capable of carrying out the objects above set forth, in the novel parts and combinations of parts disclosed and defined in the appended claims.

What is claimed is:—

1. A toy simulating a washing machine comprising a body member having a cham-

ber therein, a cover for said body member, a shaft mounted for free rotation above said cover, a gear on said shaft, a lever pivoted to said body, a bar pivoted to said lever extending over said gear and arranged for free vertical swinging movement whereby when said lever is reciprocated it will engage said gear on one stroke, but will move vertically and ride over the said gear on the opposite stroke and means on said shaft to rotate the same idly during said opposite stroke of said lever by the impulse given said shaft through said gear.

2. A toy constructed and arranged to simulate a washing machine having in combination, a body member having a chamber therein, a cover for said member, a bracket mounted on said cover, a shaft journaled for free rotation in said bracket, a ratchet gear secured to said shaft, a lever pivoted on said body, a bar pivoted to said lever and extending over said gear, said bar having ratchet teeth on its under side, the teeth on said bar and gear being oppositely directed, guiding means for said bar permitting vertical movement thereof about its pivot whereby said bar will turn said gear when moved in one direction, but will ride over said gear when moved in the other direction and a fly wheel on said shaft for rotating the same idly during said stroke of said bar in said other direction.

3. A toy constructed and arranged to simulate a washing machine having in combination, a body member simulating a clothes container, a cover for said member, a bracket mounted on said cover, a shaft freely revoluble in said bracket, a reciprocating manually operated means for rotating said shaft when moved in one direction, adapted to move idly in the opposite direction, and a fly wheel on said shaft for maintaining rotation of said shaft during said opposite movement of said means.

In testimony whereof I affix my signature.

FRANCES M. PAHL.
